UNITED STATES PATENT OFFICE.

GIDEON ALVIN FRY, OF NEW KENSINGTON, PENNSYLVANIA.

DUST-MOP.

1,143,528.

Specification of Letters Patent. Patented June 15, 1915.

Application filed February 14, 1914. Serial No. 818,740.

To all whom it may concern:

Be it known that I, GIDEON ALVIN FRY, a citizen of the United States, residing at New Kensington, in the county of Westmoreland 5 and State of Pennsylvania, have invented new and useful Improvements in Dust-Mops, of which the following is a specification.

This invention relates to mops and particularly to mop holders.

The principal object of this invention is to provide a novel type of holder for fringe mops and to construct the mop body in such manner that it may be conveniently applied 15 and removed from the holder so that it may be removed for cleaning or other purposes. Heretofore mops of this character have been constructed with a reinforcing band or wire embedded or inserted in the fringe retaining band of the mop which rendered the 20 cleaning or washing of the mop extremely difficult. Moreover in many of these types of devices the handle was permanently secured to the mop body, therefore, making 25 the cleaning operation more difficult. To avoid these difficulties I have devised a mop consisting essentially of a circular flexible band to which the fringe is attached and have provided a holder upon which such a 30 mop can be conveniently stretched and held in operative position, the shape of the holder being important in that it permits of the use of the mop in corners and other places inaccessible to the ordinary type of mop.

Further objects of the invention will appear as the following description is read in connection with the accompanying drawing, which forms a part of this application, and in which:—

Figure 1 is a side elevation. Fig. 2 is a top plan view with the handle removed. Fig. 3 is a longitudinal sectional view. Fig. 4 is a transverse sectional view taken on the line 4—4 of Fig. 2. Fig. 5 is a perspective view of the escutcheon plunger removed. Fig. 6 is a perspective view of the mop removed from the holder.

Referring more particularly to the drawing, the mop consists essentially of a continuous band of fabric 1 substantially U-shape in cross section between the walls of which is stitched the fringe 2. At diametrically opposite points in the band there are secured suitable eyelets or hollow rivets 3

and 4, the former extending through both 55 walls of the band, while the latter is riveted or secured to the inner wall of the band only. The object of thus securing the eyelets will be made more plain hereinafter.

The holder is preferably constructed of 60 some non-corrosive material and in outline is substantially heart-shaped and is generally indicated at 5, the side walls or arms 6 extending on diverging lines from the pointed end 7 as shown and curving in 65 wardly toward each other as at 8. A continuation of the side walls is shown at 9 in the form of slightly converging bars which extend from the portions 8 to the pointed end 7 and are integral with both. 70

Extending upwardly and toward each other from opposite bars 9 are arms 10 having ears 11 at their terminals which are adapted to receive the clamping screw 12. Pivotedly mounted upon this clamping screw 75 12 is the head 13 of a handle attaching bolt 14 which is threaded into the handle 15, a section only of which is shown. By removing the screw 12 the entire handle may be disconnected from the mop holder and the 80 mop used by grasping the bars 9.

Extending longitudinally through the pointed end 7 and secured therein in any suitable manner is a supporting bar 16 which lies intermediate the bars 9 and is 85 threaded upon its rear end to receive a thumb nut 17. The forward end of the bar projects beyond the pointed end, as shown at 18, to enter the hollow rivet or eyelet 4. The eyelet being only passed through the 90 inner wall of the band the projection 18 is not exposed and, therefore, cannot be brought into contact with any article to scar the same. The opposite rivet or eyelet is slidably mounted upon the rod 16 so that 95 a portion of the band may be forced into the channel between the bars 9. For this purpose I provide a slightly wedge-shaped plunger 19 slidably mounted upon the bar 16 so as to wedge the band into tight engagement with the bars and push the same toward the pointed end 7, thus stretching the band around the arms 6. 100

In order to prevent the band from becoming disengaged from the arm in practice by 105 rising above the same the arms are provided with a flange 20 at their upper edges which extends outwardly beyond the arms

and from a point midway of the length of the nose to a point midway of the portions 8.

What is claimed is:—

1. In combination with endless mop material, a frame for receiving the material therearound and of heart formation, said frame having a channel therein opening into the large end thereof and adapted to receive a portion of the mop material, and 10 means operable within the channel for holding the inserted material therein and for stretching the mop material around the frame.

2. In combination with endless mop material, a frame for receiving the material therearound and of heart formation, the said frame having a channel therein opening into the large end thereof and adapted to receive a portion of the mop material, 15 and means operable within the channel for holding the inserted material therein and for stretching the mop material around the

frame and having a portion extending through the smaller end of the frame for engaging the mop.

3. In combination with endless mop material, a frame for receiving the material therearound and of heart formation, said frame having a channel therein opening into the large end thereof and adapted to receive 20 a portion of the mop material, means operable within the channel for holding the inserted material therein and for stretching the mop material around the frame, and means on the frame for preventing the upward creeping of the mop material when positioned upon the frame.

In testimony whereof I affix my signature in presence of two witnesses.

GIDEON ALVIN FRY.
